UNITED STATES PATENT OFFICE.

CHARLES GILBERT HAWLEY, OF CHICAGO, ILLINOIS, ASSIGNOR TO LOCOMOTIVE FIRE-
BOX COMPANY, OF CHICAGO, ILLINOIS, A CORPORATION OF DELAWARE.

LOCOMOTIVE-BOILER FIRE BOX.

Application filed May 13, 1922. Serial No. 560,656.

My invention relates to locomotive boilers which are equipped with the so-called Nicholson thermic siphon, or the like, comprising a water-steaming-and-circulating wall which depends from the crown sheet of the firebox and which receives water from the lower part of the boiler, delivering same upon the crown sheet of the firebox. In particular, this invention relates to an improvement which is applicable to and which facilitates the installation of such water-circulating devices upon fireboxes of the Bellpaire type; that is, such as have practically flat-topped wrapper sheets. In installing siphons in such fireboxes a peculiar difficulty is encountered. Not only must the crown sheet of the firebox and the siphon be well supported against the bursting pressure of the contained steam, but likewise the flat top of the boiler must also be stay-bolted or otherwise supported against the steam pressure. The object of my invention is to obviate this difficulty and to provide adequate supports for both the internal and external sheets of the boiler and firebox.

My invention will be readily understood on reference to the accompanying drawings in which Fig. 1 is a vertical longitudinal section of a locomotive boiler of the Bellpaire type, equipped with Nicholson thermic siphons. Fig. 2 is a cross section thereof. Fig. 3 is an enlarged cross sectional detail taken from the upper part of Fig. 2. Fig. 4 is a side view of the parts shown in Fig. 3 and Fig. 5 illustrates a slightly modified construction.

A Bellpaire firebox is distinguished by a substantially flat crown sheet 2 and a substantially flat outside wrapper sheet 3. The thermic siphons 4, 4 here shown are applied according to standard practice, which is to remove one longitudinal row of crown bolts and use the adjacent rows 5, 5 in the top flange of the siphon. So to do would leave the intervening portion 3^x of the wrapper sheet unsupported. To obviate this difficulty I employ a substitute middle row of crown bolts 5', the upper ends of which are secured in the wrapper 3, while the lower ends are attached to certain of the stay-bolts 4' in the top of the thermic siphon. Either several or all of the stay-bolts 4' in the upper row in the siphon may be thus employed. By preference I substitute for the threaded stay-bolts usually employed in the

top row of the siphon a row of strong rivets 6, which pass through sleeves or ferrules 7. The latter serve to space the sides of the siphon apart and each thereof is provided with a boss 7', which receives the threaded lower end of the stay-bolt 5'. This structure is simple and economical and easy to install initially.

As a substitute construction, I have devised that shown in Fig. 5, wherein I employ a stay-bolt 5^x of the flexible type. The lower end of the stay-bolt is provided with an eye 5^y through which the standard stay-bolt 4' passes. The upper end of the stay-bolt 5^x is threaded and receives the ball nut 8. The latter makes it possible to adjust the bolt accurately, and obviously rests within the socket 9, which is secured in the wrapper 3.

I call attention to the fact that this present invention is adapted not only to a standard siphon having the top flanges 4^x depicted in Fig. 3, but is also adapted for employment with a flangeless siphon as depicted in Fig. 5 and as more fully discussed in my companion application entitled Locomotive fireboxes, S. N. 560,655.

Although I have described this invention as applicable to fireboxes of the Bellpaire or flat-topped type, I desire that it be understood that the invention may also be used upon fireboxes of boilers of the wagon-top type, particularly in cases where a comparatively thin wrapper sheet is used.

Having thus described my invention, I claim as new and desire to secure by Letters Patent:

1. A locomotive firebox having a crown sheet and a spaced wrapper sheet in combination with a thermic siphon positioned in the firebox, said thermic siphon being composed of spaced, vertically disposed and longitudinally arranged walls opening through the crown sheet, staybolts connecting said spaced siphon walls and a row of stays arranged in the median plane of the siphon and anchored at their top ends in the wrapper sheet and directly connected to the topmost staybolts connecting said spaced siphon walls.

2. A locomotive firebox having a crown sheet and a spaced wrapper sheet in combination with a thermic siphon positioned in the firebox, said thermic siphon being composed of spaced, vertically disposed and

longitudinally arranged walls opening through the crown sheet, ferrules extending between the walls of the siphon to space them apart and each including a boss, rivets 5 passing through the said ferrules, and said siphon walls respectively and a row of stay bolts arranged in the median plane of the

siphon and each threaded at one end to a ferrule boss and at the other end operatively connected to the wrapper sheet. 10

In testimony whereof, I have hereunto set my hand this 6th day of May, 1922.

CHARLES GILBERT HAWLEY.
